Attorney

UNITED STATES PATENT OFFICE.

FRANCIS F. HAMILTON, OF INDIANAPOLIS, INDIANA.

MUFFLER.

Application filed March 15, 1928. Serial No. 261,752.

This invention relates to means for muffling the noise of gases exhausted from gas engines and the like and has for its primary purpose not only the muffling of the sound 5 but also the prevention of back pressure of the exhaust gases.

The invention is described in reference to the accompanying drawing, in which—

Fig. 1 is a fragmentary top plan view of 10 one form of a muffler embodying my invention;

Fig. 2, a fragmentary top plan view of a modified form of the intake end of the muffler; and

Fig. 3, a transverse vertical section 15 through the muffler on the line 3—3 in Fig. 1.

Like characters of reference indicate like 20 parts throughout the several views in the drawing.

I form an outer housing 5 having a transverse cross section preferably of an irregular curved shape as shown in Fig. 3. The intake end of the housing 5 is closed by a 25 head 6 which is curved or bulged outwardly from its outer edges from the housing end, and thence sharply inwardly toward a point decided to one side away from the central axis of the housing, and an intake pipe 30 7 is entered through the head 6 at this point to extend for a substantial length therein, a tight joint being made between the head 6 and the pipe 7.

Within the housing 5 is positioned an ex- 35 pansion chamber 8 similar in shape to the housing 5 but having a smaller volume so that there is a continuous space around and between the chamber 8 and the housing 5 of substantially the same width throughout.

This chamber 8 is spaced inwardly from 40 the head 6 so that there is a space defined between the forward flat end 9 of the chamber 8 and the curved head 6, which space is in communication around the edges of the 45 end 9 with the longitudinal circumferential space between the chamber 8 and the housing 5.

The pipe 7 extends to within the chamber 8 for a substantial distance as indicated 50 in Fig. 1. The opposite or rear end of the chamber 8 has an outwardly bulged head 10 which has an inner concave face presented inwardly against which the gases discharged from the end of the pipe 7 are directed. The center of curvature of the inner face lies upon the axial center line of

the pipe 7 substantially at its discharging end or just to the rear of the end.

The chamber 8 is made gas tight throughout and to permit the gases to escape therefrom, a plurality of holes 11 are formed through the forward head 9 immediately around the pipe 7, Fig. 3, the total area of all the holes 11 being equal to or greater than that of the cross sectional area of the 65 pipe 7.

By placing the pipe 7 down and off to near one side of the housing 5 and chamber 8, gases discharging from the chamber 8 into the forward space against the housing 70 head 6, and by the aid of the curvature of the head 6, are deflected back around the sides of the chamber 8 along the housing 5. It is obvious that the gas is differentiated or spread out, some taking the shortest path 75 "A" and some of the longest path "B" (Figs. 1 and 3), all of the gas travelling to the rear of the housing 5 and heat being dissipated from the gases through the wall of the housing 5. 80

The gases coming the paths of various lengths are integrated, that is summed up, or collected together behind the rear end of the chamber 8 by the rearwardly extended conical-like housing end 12 which has its 85 apex on the extended center line of the pipe 7. A discharge or tail-pipe 13 is fitted to the end 12 at the apex to have its center line coincide with that of the pipe 7. By so positioning the pipe 13 in reference to the 90 pipe 7, gases that go the path "B" travel a farther distance through the muffler than do the gases travelling the path "A" and hence the "B" stream does not arrive until after the "A" stream has arrived in the pipe 13. 95

In some cases I find it advisable to place a layer of material 14, such as asbestos, around the inner side wall of the chamber 8, which material is retained by the coarse screen 15. By this means, a rough, porous 100 facing is obtained around the chamber wall so that all sound not otherwise broken up and eliminated is thereby absorbed.

Where a cheaper construction is required, the modified form as shown in Fig. 2 is employed, to have a flat housing forward head 16, and to be without a chamber wall sound deadener.

While I have here described my invention in the one precise form as now best known 110 to me, it is obvious that many structural changes may be made without departing

from the spirit of the invention, and I, therefore, do not desire to be limited to the precise structure as shown and described, nor any more than may be necessitated by 5 the following claims.

I claim:

1. In a muffler of exhaust gases, a housing closed at both ends, an expansion chamber within the housing defining a passageway 10 therearound throughout its length between the chamber and the housing, an intake pipe entering the housing and front end of the chamber to have its discharge end within the chamber and directed toward the rear end of 15 the chamber, said intake pipe entrance into said chamber being considerably to one side of the central-most axis of the chamber, said chamber having a discharge opening therefrom at its forward end, and the rear 20 end of said housing having a discharge opening therefrom.

2. In a muffler of exhaust gases, a housing closed at both ends, an expansion chamber within the housing defining a passageway 25 therearound throughout its length between the chamber and the housing, an intake pipe entering the housing and front end of the chamber to have its discharge end within the chamber and directed toward the rear 30 end of the chamber, said intake pipe entrance into said chamber being considerably to one side of the central-most axis of the chamber, said chamber having a discharge opening therefrom at its forward end, and 35 the rear end of said housing having a discharge opening therefrom, and insulating means around said expansion chamber.

3. In a muffler of exhaust gases a housing closed at both ends, an expansion chamber 40 within the housing defining a passageway therearound throughout its length between the chamber and the housing, an intake pipe entering the housing and front end of the chamber, to have its discharge end within 45 the chamber and directed toward the rear end of the chamber, said intake pipe entrance into said chamber being considerably to one side of the central-most axis of the chamber, said chamber having discharge 50 openings therefrom at its forward end, and the rear end of the housing having a discharge opening therefrom, and the rear end of said chamber being concave to have its center of curvature within the chamber sub- 55 stantially on the center line of said intake pipe.

4. In a muffler of exhaust gases, a housing closed at both ends, an expansion chamber within the housing defining a passageway 60 therearound throughout its length between the chamber and the housing, an intake pipe entering the housing and front end of the chamber to have its discharge end within the chamber and directed toward 65 the rear end of the chamber, said intake

pipe entrance into said chamber being considerably to one side of the central-most axis of the chamber, said chamber having discharge openings therefrom at its forward end, and the rear end of the housing having a discharge opening therefrom, the rear 70 end of said chamber being concave to have its center of curvature within the chamber substantially on the center line of said intake pipe, and insulating means around said 75 expansion chamber.

5. In a muffler of exhaust gases, a housing closed at its forward end, an expansion chamber within the housing spaced therein to define a space therearound and at its forward end between it and the housing, an intake pipe entering the housing and discharging to within the chamber, a wall of 80 said chamber having a concave face directed toward the discharge end of said intake pipe, the center of curvature of the face being substantially on the center line of the pipe, said chamber having discharge openings 85 therefrom in the wall opposite said concave face whereby gases escaping from the chamber are directed toward the front end of 90 said housing, and a collecting head on the rear end of the housing having a discharge opening therefrom, said discharge opening being on the center line of said intake pipe 95 and said intake pipe entrance being considerably to one side of the central longitudinal axis of said housing and chamber.

6. In a muffler of exhaust gases, a housing closed at its forward end, an expansion 100 chamber within the housing spaced therein to define a space therearound and at its forward end between it and the housing, an intake pipe entering the housing and discharging to within the chamber, a wall of said 105 chamber having a concave face directed toward the discharge end of said intake pipe, the center of curvature of the face being substantially on the center line of the pipe, said chamber having discharge openings therefrom in the wall opposite said concave face whereby gases escaping from the chamber are directed toward the front end of said 110 housing, and a collecting head on the rear end of the housing having a discharge opening 115 therefrom, said discharge opening being on the center line of said intake pipe and said intake pipe entrance being considerably to one side of the central longitudinal axis of said housing and chamber, and insulating means around said chamber.

7. In a muffler of exhaust gases, a housing closed at its forward end, an expansion chamber within the housing spaced therein to define a space therearound and at its forward end between it and the housing, an intake pipe entering the housing and discharging to within the chamber, a wall of 125 said chamber having a concave face directed toward the discharge end of said intake 130 pipe.

pipe, the center of curvature of the face being substantially on the center line of the pipe, said chamber having discharge openings therefrom in the wall opposite said 5 concave face whereby gases escaping from the chamber are directed toward the front end of said housing, and a collecting head on the rear end of the housing having a discharge opening therefrom, said discharge 10 opening being on the center line of said intake pipe and said intake pipe entrance being considerably to one side of the central longitudinal axis of said housing and chamber, said chamber discharge openings 15 being grouped around said intake pipe.

8. In a muffler of exhaust gases, a housing closed at its forward end, an expansion chamber within the housing spaced therein to define a space therearound and at its for- 20 ward end between it and the housing, an intake pipe entering the housing and discharging to within the chamber, a wall of said chamber having a concave face directed toward the discharge end of said intake pipe, 25 the center of curvature of the face being substantially on the center line of the pipe, said chamber having discharge openings therefrom in the wall opposite said concave face whereby gases escaping from the chamber 30 are directed toward the front end of said housing, and a collecting head on the rear end of the housing having a discharge opening therefrom, said discharge opening being on the center line of said intake pipe and 35 said intake pipe entrance being considerably to one side of the central longitudinal axis of said housing and chamber, said intake pipe projecting a substantial distance into said chamber and said chamber discharge openings being grouped around said intake 40 pipe.

9. In a muffler of exhaust gases, a housing closed at its forward end, an expansion chamber within the housing spaced therein to define a space therearound and at its forward end between it and the housing, an intake pipe entering the housing and discharging to within the chamber, a wall of said chamber having a concave face directed toward the discharge end of said intake pipe, 45 the center of curvature of the face being substantially on the center line of the pipe, said chamber having discharge openings therefrom in the wall opposite said concave face whereby gases escaping from the chamber 50 are directed toward the front end of said housing, and a collecting head on the rear end of the housing having a discharge opening therefrom, said discharge opening being on the center line of said intake pipe and said intake pipe entrance being considerably to one side of the central longitudinal axis of said housing and chamber, and said housing forward head being formed to deflect gases from the chamber to entirely 55 around the longitudinal passageway between said chamber and said housing.

In testimony whereof I affix my signature.

FRANCIS F. HAMILTON.
